(57) CLAIM

The ornamental design for a storage container, as shown and described.

DESCRIPTION

FIG. 1 is a front-top-right perspective view of the storage container of the present disclosure;

FIG. 2 is a top planar view of the storage container of the present disclosure;

FIG. 3 is a bottom planar view of the storage container of the present disclosure;

FIG. 4 is a front planar view of the storage container of the present disclosure;

FIG. 5 is a rear planar view of the storage container of the present disclosure; and,

FIG. 6 is a left side planar view of the storage container of the present disclosure (the right side planar view is a mirror image).

Where applicable, features shown in broken lines are for illustrative purposes only and form no part of the claimed design.
